UNITED STATES PATENT OFFICE

GEORGE MOSTOWY, OF WINNIPEG, MANITOBA, CANADA

BUILDING BRACKET

Application filed January 10, 1929, Serial No. 331,525, and in Canada August 14, 1928.

The invention relates to improvements in building brackets and an object of the invention is to provide a simply constructed, inexpensive, relatively light but durable bracket which can be folded when not in use and readily opened when it is to be used and which will effectively support an operating platform when suspended from a wall.

With the above more important object in view, the invention consists essentially in the arrangement and construction of parts hereinafter more particularly described, reference being had to the accompanying drawing, in which:

15 Fig. 1 is a perspective view of the bracket as it appears in suspended position.

Fig. 2 is an enlarged detailed sectional view showing the joint formed between the upwardly and outstanding bars.

20 Fig. 3 is an enlarged detailed vertical sectional view through the upper end of one of the upstanding bars and the adjacent end of the outstanding bar.

In the drawing like characters of reference 25 indicate corresponding parts in the several figures.

In forming the bracket, I provide a pair of upstanding bars 1 and 2, a pair of outstanding bars 3 and 4 and a single brace bar 30 5. The bars are preferably of angle iron and the lower ends of the inturned flanges of the bars 1 and 2 are lapped and are pivotally connected together by a bottom bolt 6, such permitting of said bars being folded together when not in use.

The upper ends of the bars 1 and 2 are 35 provided with key hole slots 7 and 8 utilized to receive supporting nails 9 and 10 driven into a wall 11 or other vertical structure. The bars 3 and 4 have the horizontal flanges lapped at their forward ends and pivotally connected together by a bolt 12, such arrangement permitting of the bars being folded together. The inner ends of the 40 bars 3 and 4 have their vertical flanges pivotally connected to the upper ends of the outstanding flanges of the bars 1 and 2, the pivot connections being made in each instance by a bolt 13 which permits of a limited amount 45 of loose play at the connection, that is, which

permits a limited side swinging of the bars 3 and 4 in respect to the outstanding flanges of the bars 1 and 2.

The brace bar 5 has the vertical flange thereof cut away at the upper end and the remaining flange outturned and underlying the horizontal flange of the bar 3 and fastened to the bars 3 and 4 pivotally by the bolt 12. The lower end of the vertical flange of the bar 5 is also cut away and the other flange 60 is down turned and is fastened to the inturned flanges of the bars 1 and 2 by the bolt 6.

In practice, a pair of brackets would be used to support a platform from a wall and at such time, one would drive the nails 9 and 10 into the wall spacing them a sufficient distance apart to hold the upper ends of the bars 1 and 2 well spread as shown in Figure 1. It will be observed that the bracket is simply caught on the nails by passing the heads of the nails through the large ends of the key hole slots and passing them up into the contracted ends, the heads of the nails at such time preventing the bars from escaping outwardly. When the brackets are in place, the bars 1 and 2 rest against the wall, the bars 3 and 4 are spread to effectively support the boards placed thereon and the brace bar 5 effectively holds up the forward ends of the bars 3 and 4. I have shown in dotted outline Figure 1, three boards resting on the horizontal bars 3 and 4 of the bracket.

When the device is not in use, the bars 1 and 2 are folded towards one another and the device takes but little room.

What I claim as my invention is:

1. A building wall bracket comprising a pair of upstanding bars each presenting a wall engaging flange and an outstanding flange at right angles thereto and having the wall engaging flanges thereof lapped at their lower ends and pivotally connected together and their upper ends provided with key hole slots, a pair of horizontally disposed bars each presenting an inturned and a down turned flange and having the inturned flanges thereof lapped at their forward ends and pivotally connected together and the down turned flanges thereof pivotally connected at their inner ends to the outstanding flanges

of the upright bars and a brace bar extending between the pivotally connected ends of the horizontal bars and the pivotally connected ends of the vertical bars.

5 2. A building wall bracket comprising a pair of upright bars each presenting a wall engaging flange and an outstanding flange at right angles thereto and having their wall engaging flanges lapped at the lower ends of
10 the bars and pivotally connected together by a pivot bolt and said inturned flanges at the upper ends provided with key hole slots, a pair of horizontally disposed bars each presenting an inturned and a down turned flange
15 and having the inturned flanges thereof lapped at their forward ends and pivotally connected together by a pivot bolt and the down turned flanges thereof pivotally connected at their inner ends to the outturned
20 flanges of the vertical bars by pivot bolts and a brace bar extending between the pivotally connected forward ends of the horizontal bars and pivotally connected lower ends of the vertical bars and fastened thereto by the
25 pivot bolts forming the pivot fastenings at such latter points.

Signed at Winnipeg, this 17th day of December, 1928.

GEORGE MOSTOWY.
